UNITED STATES PATENT OFFICE.

PAUL S. DOUGHERTY, OF CHICAGO, ILLINOIS, ASSIGNOR TO STANDARD GALVANIZING CO., OF CHICAGO, ILLINOIS, A CORPORATION OF ILLINOIS.

REFRIGERATOR-CAR DRAIN.

Application filed November 10, 1924. Serial No. 749,001.

To all whom it may concern:

Be it known that I, PAUL S. DOUGHERTY, a citizen of the United States of America, and a resident of Chicago, in the county of 5 Cook and State of Illinois, have invented a new and useful Improvement in Refrigerator-Car Drains, of which the following is a specification.

The main object of this invention is to 10 provide for refrigerator cars an outlet drain from the floor pan which will be trapped; to provide a construction formed from sheet steel; to provide a trap having a minimum number of parts of light weight 15 of low expense in the construction, and of convenient form for installation on the standard refrigerator car; to provide a trap which is adapted to be positively secured to the floor pan in a refrigerator car; to provide 20 a trap in which the sealing bowl is below the body or platform of the car; to provide a bowl or seal of symmetrical form which is readily accessible and easily 25 cleaned; to provide a counter poise on the bowl so that the bowl is normally held in 30 position so as to form a perfect trap for the drain; and to provide an inexpensive construction with maximum durability.

One of the objects obtained by this invention 35 is the construction of a sanitary refrigerator car drain with a trap in which there is no internal bowl or inaccessible pockets in which decaying matter can lodge and become the source of infection.

35 An illustrative embodiment of this invention is shown in the accompanying drawings, in which—

Fig. 1 is a complete trap secured to the 40 pan of the car projecting through the sill with the bowl in position to form a seal.

Fig. 2 is the same trap with a bowl 45 swung to one side against the force of the counter weight, putting the bowl in such position that it will clean itself.

45 In Fig. 1 the floor pan 1 is shown resting on the platform sill 2. An aperture through the bottom of the floor and the sill is made sufficiently large to pass the drain pipe 3 and hinge 4 when the bowl 5 is removed from the trap. The drain pipe 3 is inserted from the top and a water tight joint is made between the flange 6 and the floor pan 1, such water tight joint being formed by the use of solder, rivets or by 50 nails through the flange and bottom into

the sill. The method of securing the flange 6 to the bottom is a matter of expediency and convenience. When the drain tube 3 is inserted and secured to the pan, the bowl 5 is detachably attached to the drain pipe 60 and is locked in place by the insertion of the pivot in the hinge 4. The hinge 4 has two leaves one of which is secured to the drain pipe and the other leaf is arranged to permit the bowl 5 to swing downwardly 65 and outwardly entirely clear of the lower end of the drain pipe for cleaning the device. The bowl 5 has attached thereto a bracket 7 secured by a rivet 8. The bracket 7 supports a counter poise 9 which is of sufficient weight and occupies a position which will normally hold, through the action of gravity, the bowl in the position shown in Fig. 1. The weight is approximately L-shaped and one of its arms is attached exteriorly of the projecting bracket and abuts against the bowl adjacent the said bracket and its other arm extends upwardly and is arranged to clear the bottom of the car when the bowl is swung away from the 70 lower end of the drain. The end of the drain pipe on the side opposite to the hinge 4 is provided with a projection or stop 10 which normally coacts with the bottom of the bowl 5 and limits the upward motion of 75 the bowl to the position where the bowl is normally horizontal. The hinge 4 is secured to the drain pipe 3 by rivets 11 which are above the normal water level.

In the construction as shown in this invention, the drain pipe, the bowl, the hinge and the bracket supporting the counter weight are all formed from sheet steel. In the forming, care is taken that the radius of bend shall at all times be greater than 90 twice the thickness of the drawn metal. In operation the bowl normally holds the position, as shown in Fig. 1, and the drain water which escapes by way of the drain pipe 3 fills the bowl to its upper edge and forms a seal so that there is no current of air through the drain pipe into the refrigerator car. In operation the bowl naturally becomes the settling basin for animal and vegetable material and such material 95 will rapidly decay. Hence it is necessary to provide a construction from which the decaying matter can be conveniently removed. For this purpose the bowl is located below the sills of the car where an 100 105 110

attendant can easily reach and clean the bowl, and at the same time see that the bowl is thoroughly cleaned. When the bowl is swung to its side position, the drain pipe has a perfectly straight opening up into the bend and any material which is lodged in the drain pipe can be seen and removed by a brush or stock. Since refrigerator cars are used for the transportation of fresh meats and vegetables, it is of great importance that the entire outfit be kept as sanitary as possible and that decayed matter be thoroughly removed before it reaches the infection stage.

One of the most practical features of the external bowl-type of refrigerator trap is based on the fact that when the car is loaded and sealed, clogging of the drain pipe results in damage to the contents of the car.

With this construction there is a normal static water head of about eighteen inches which is capable of removing the usual obstructions in the bowl by static pressure. In case overflow of the floor pan is observed, it is not necessary to open the sealed car in order to clean out the drain.

Although but one specific embodiment of this invention is herein shown and described, it will be understood that numerous details of the construction shown may be altered or omitted without departing

from the spirit of this invention as defined by the following claim.

I claim:

A refrigerator car trap comprising a drain pipe having its lower portion extending below the bottom of the car, a two-leaf hinge having one of its leaves secured to the projecting portion of the drain pipe above the lower end thereof, the other leaf of the hinge being movable, a bowl secured at one of its side walls to the movable leaf of the hinge, and normally arranged in a horizontal position at the lower end of the drain pipe and receiving the same, a bracket carried by the bowl and projecting outwardly from the same exteriorly thereof adjacent the movable leaf of the hinge, an approximately L-shaped weight secured at one arm to the projecting portion of the bracket and fitted against the exterior of the bowl contiguous to the bracket and normally maintaining the bowl in the said horizontal position, the other arm of the weight projecting upwardly and being of the size to clear the car and permit the bowl to swing entirely clear of the lower end of the drain pipe for cleaning the device.

Signed at Chicago this 7th day of Nov., 1924.

PAUL S. DOUGHERTY.
